Patented Sept. 26, 1967

208,747

ELECTRIC MANICURIST CASE OR SIMILAR ARTICLE

William V. Judson, Westport, Conn., assignor to General
Electric Company, a corporation of New York

Filed May 12, 1966, Ser. No. 2,271

Term of patent 3½ years

(Cl. D86—10)

FIG. 1

FIG. 2

FIG. 3

FIG. 4

FIG. 5

FIG. 6

FIG. 7

FIG. 8

FIG. 1 is a top perspective view of an electric manicurist case embodying my new design;

FIG. 2 is a top plan view thereof;

FIG. 3 is a front elevational view thereof;

FIG. 4 is a side elevational view thereof;

FIG. 5 is a rear elevational view thereof;

FIG. 6 is a bottom plan view thereof;

FIG. 7 is a front perspective view showing the inside of the case; and

FIG. 8 is a top plan view showing the inside of the case.

I claim:

The ornamental design for an electric manicurist case or similar article, substantially as shown.
